UNITED STATES PATENT OFFICE.

HEINRICH KELLERMANN, OF BERLIN, GERMANY.

TOY WITH SPARKING DEVICE.

Application filed April 3, 1922. Serial No. 549,215.

To all whom it may concern:

Be it known that I, Dr. HEINRICH KELLERMANN, chemist, citizen of Hungary, residing at Berlin, in Prussia, Germany, have invented new and useful Improvements in a Toy with Sparking Device, of which the following is a specification.

This invention relates to a toy in which one part of a pyrophorous sparking device is connected with a part adapted to be rotated by hand, the other part of the sparking device being stationary with regard to the first part or movable in a different manner so that sparks are produced by the movement of the 15 rotatable part of the toy.

According to the invention the pyrophorous mass, the so called scintillant stone, is rotatably arranged in such a manner that it will rotate in the form of a circle and that in 20 its rotation sparks are produced along a circle, whereby special effects are obtained. With a view to attain this object the pyrophorous sparking device is connected with a device consisting of a handle and a swinging 25 arm rotatably connected with said handle, in such a manner that if the swinging arm is turned around the handle the one part of the sparking device is moved along the other part thereof.

The spark producing device may also be 30 connected with other known toys or mounted on or in the same, for instance with a child's rattle, so that when the device is operated the rattling noise is produced simultaneously with the sparks.

In order that the invention may be clearly understood, I shall proceed to describe the same with reference to the several forms of construction shown by way of example on 40 the accompanying drawings, wherein:—

Fig. 1 is a side elevation partly in section of a simple form of construction of the improved toy.

Fig. 2 is a plan view of Fig. 1.

Figs. 3 and 4 show in plan view and in section a second form of construction.

Figs. 5 and 6 illustrate the combination of the spark producer with the toy rattle.

Figs. 7 and 8 show in side elevation and 50 plan view respectively a modified form of construction.

Fig. 9 shows in side elevation a further form of construction, the pyrophorous mass being movably arranged with regard to the 55 swinging arm.

Figs. 10 and 11 show a similar form of con-

struction in side elevation and plan view respectively.

In the toy illustrated in Figs. 1 and 2 a small friction or scratcher wheel 3 is mounted upon the fixed axle 2 of a handle 1 and consists of a steel disk with milled or otherwise roughened convex surface or of a wood disk with a cover of emery-paper or -cloth on its convex surface. Upon the axle 2 of the handle 1 a socket 4 is loosely arranged, which is shown in Fig. 1 in longitudinal section, and in this socket the pyrophorous mass 5, which preferably consists of a piece of cerium alloy, e. g. iron-cerium, is located and 70 pressed in the well known manner by the action of a spring 6 against the friction wheel 3. The socket 4 is mounted by its arms 7 upon the axle 2 so that it can turn around this axle. At the outer end of socket 4, for 75 instance upon the screw cap 8, an arm 9 is fixed which carries at its end a weight 10 serving as fly body.

The toy is used in the following manner:—

The handle 1 is gripped with one hand and 80 the fly-weight 10 is swung round so that the arm 9 with the socket 4 and the scintillant stone 5 rotates around the friction wheel or scratcher 3. Consequently sparks are continuously produced along a circular path. 85 It is evident that the socket 4 or the arms 7 of the same must be arranged in such a manner that the sparks are always visible. If the production of the sparks has to be interrupted at certain points of the circumference of the wheel, the corresponding parts of the wheel rim are smooth, that is to say not roughened or not covered with emery-paper or the like so that the scintillant stone moves along these parts of the friction wheel 90 without producing sparks. Such a construction of the friction wheel can be used also in connection with the forms of construction 95 which will be hereinafter described.

Figs. 5 and 6 illustrate the combination of 100 the simple toy shown in Figs. 1 and 2 with an ordinary child's rattle. Upon the axle 12 of the handle 11 not only the usual toothed wheels 13 of the rattle, but also the friction wheel 14 for the spark producing 105 device are mounted. In the form of construction shown the friction wheel 14 is arranged outside the frame 15 of the rattle above a rope pulley 16. Upon the surface of the frame 15 of the rattle the socket 17 110 for the scintillant cerium stone 18 is fixed. The socket with its contents are constructed

as hereinbefore described. The rope pulley 16 is connected with a second rope pulley 20 by means of an endless rope or string 19, said second rope pulley being loosely mounted upon an axle 21 fixed in the frame 15. The second rope pulley 20 is rigidly connected with the second friction wheel 22 against which a scintillant stone 23, mounted in a socket or sleeve 25 shown in section in Fig. 5, is pressed by the action of a spring 24. The sleeve 25 is fixed upon the frame 15. As the rope pulley 20 and the friction wheel 22 rigidly connected with the same does not only rotate around the axle 12 if the rattle 5 is being swung, but also rotates around its own axle 21 and rotates consequently also relatively to the scintillant stone 23, which swings around the axle 12 together with the rattle, sparks will also be produced by this 10 second pyrophorous sparking device along a circle path. In this manner two spark circles are produced which are situated eccentrically to one another, one of these circles at the same time going round the other. 15 In a similar manner several other spark circles can be produced. It is evident that several spark circles can be produced also in cases where the toy is not combined with a rattle. The movement can be transmitted 20 from the axle of the handle upon the axles of the other friction wheels with the aid of sprocket wheels and chains or of toothed wheels or of friction wheels in gear with one another, instead of the shown transmission. On the other hand the combination 25 of the toy with the child's rattle can be used also for the production of only one spark circle, in which case the rope pulleys or other transmission means are unnecessary. 30 In the form of construction shown in Figs. 7 and 8 the swinging arm consists of a strip of sheet metal which is bent in U-shape to form a frame. The ends of the arms *a* and *a'* of this frame are rotatably mounted upon 35 the axle *e* of handle *f*. The friction wheel *m* in this case is not mounted upon the axle *e* of the handle *f* but upon a separate shaft *n* which is journaled in the arms *a*, *a'* of the swinging frame. A toothed wheel *g* is 40 keyed upon the axle *e* and engages with a pinion *h* keyed upon an intermediary shaft *o*. A toothed wheel *h'* also keyed upon this intermediary shaft *o* serves for transmitting 45 the movement to a pinion *i* of the shaft *n*. The scintillant stone 18 is mounted in a sleeve *p* which is pressed by the action of 50 a spring *r*, fixed upon the arm *a*, against the circumference of the friction wheel *m* which is also arranged above this arm *a*. 55 Upon the axle *e* of the handle *f* a toothed wheel *l* is further arranged which meshes with an elastic blade of sheet metal *k* fixed 60 between the arms *a*, *a'*. Owing to the toothed wheel transmission 65 the shaft *n* with the friction wheel *m* will

be rapidly rotated if the swinging frame *a*, *a'* is swung around the axle *e* of the handle *f*, the scintillant cerium stone 18 rotating with the swinging frame. In consequence of this relative movement of the friction wheel *m* with regard to the cerium stone a great number of large sparks is produced which sparks together form a circle as the cerium stone 18 moves in a circle around the handle *f*. A rattling noise is produced at the same time by the blade of sheet metal *k* sliding along the teeth of the wheel *l*. 75

In the form of construction shown in Figs. 3 and 4 several sockets 27, one of which is shown in section, are fixed like the spokes of a wheel upon the fixed axle 28 of the handle 26. A wheel loosely mounted upon the axle 28 of handle 26 carries the friction surfaces 29. In the form of construction shown these friction surfaces are arranged upon the inner surface of the wheel rim 30 which is opposite the scintillant stones 31 as can be seen from Fig. 4, the spokes 32 of the wheel passing along the sockets 27. Upon the outer surface of the wheel rim 30 a swinging arm 9 with fly-weight 10 corresponding to that shown in Figs. 1 and 2 is fixed. The friction surfaces 29 do not form a continuous ring or crown but are interrupted by smooth surfaces so that the sparks are not produced continuously, whereby an economy of scintillant stone is ensured. The arrangement is such that the scintillant stones can freely pass from the friction surfaces to the smooth surfaces of the wheel rim 30. 90 95 100

But the inner surface of the wheel rim 30 could also be entirely made as friction surface. On the other hand the scintillant stones can be arranged movable and the friction surface stationary so that with this form of construction too, a circle of sparks could be produced. The friction surfaces interrupted by smooth parts can be further arranged in such a manner that always at least one scintillant stone is in contact with a friction surface when the toy is being used so that sparks are continuously produced. 105 110 115

In the form of construction shown in Fig. 9 the swinging arms *a*, *a'*, the handle *f*, the toothed wheels and pinions *g*, *h*, *h'*, *i*, the ratchet wheel *l* and the pawl or blade *k* are arranged and constructed as described with reference to Figs. 7 and 8. The scintillant stone and its sleeve *p* are revolvably mounted by means of a blade spring *d* upon the shaft *n* which carries the pinion *i*. The blade spring *d* presses the rotating scintillant stone against the abrasive friction mass or scratcher *c* which is directly arranged upon the outer surface of the swinging arm *a*. 120 125 130

The construction shown in Figs. 10 and 11 is similar to that shown in Fig. 9 with the difference however that the support of the

pyrophorous mass here consists of a revolute rod *d* which carries upon its ends the sleeves *b* and *b'* for two scintillant stones. These sleeves *b* and *b'* are adapted to be displaced in slots *d''* of rod *d* as can be seen from Fig. 11 and they can be fixed in any convenient position by means of screws. This sparking device proper rotates with the shaft which carries the pinion *i* and which has a nut *d'* upon the upper end. The elastic pressure of the scintillant stones against the friction surface is produced by the individual elasticity of the swinging frame *a*, *a'*, whereby the part *a* of this arm is pressed against the lower surface of the scintillant stones. This pressure can be regulated by means of the nut *d'*. The friction or scratcher surface itself here consists of a strip of sand-paper, emery-paper or the like which is held in flaps *n* of sheet metal which can be stamped out of the material of the swinging arm *a*.

A similar arrangement of pyrophorous mass and friction plate can be provided upon the outer surface of the part *a'* of the swinging frame so that sparks then will be produced at both sides of the swinging frame, both spark producing devices being operated from the same shaft so that only one driving mechanism and no separate spring are wanted for both devices.

The spark producing device can be mounted in transparent or translucent cases consisting for instance of coloured glass panes. Reflectors, reflecting spheres and similar means can be arranged in the swinging arms or in the bearings for the scintillant stones or at other convenient points in order to increase the effect of the sparks.

Having now particularly described and ascertained the nature of my said invention, I declare that what I claim is:—

1. In a toy with a spark producing device formed of pyrophorous mass and scratcher, a handle, a swinging arm rotatably arranged on said handle, a wheel fixed on the axle of said handle, a second wheel of smaller diameter arranged on said swinging arm, said second wheel being in engagement with said first named wheel, one of said parts of the spark producing device being connected with said second wheel, and the other part of the spark producing device being arranged on said swinging arm.

2. In a toy with a spark producing device formed of pyrophorous mass and scratcher, a handle, a swinging arm rotatably arranged on said handle, a wheel fixed on the axle of said handle, a shaft arranged on said swinging arm parallel to the axis of said handle, a second wheel of smaller diameter on said shaft, said second wheel being in engagement with said first named wheel, one of the parts of the sparking device being connected with said second wheel, and the

other part of the spark producing device being arranged on said swinging arm.

3. In a toy with a spark producing device formed of pyrophorous mass and scratcher, a handle, a swinging arm rotatably arranged on said handle, a toothed wheel fixed on the axle of said handle, a second toothed wheel of smaller diameter than said first one and in engagement therewith, a shaft mounted in said swinging arm, said shaft being connected with said second toothed wheel of smaller diameter, one of said cooperative parts of the spark producing device arranged on and the other part of said spark producing device being fastened to said swinging arm.

4. In a toy with a spark producing device formed of pyrophorous mass and scratcher, a handle, a swinging arm rotatably arranged on said handle, a toothed wheel fixed on the axle of said handle, a second toothed wheel of smaller diameter than said first one and in engagement therewith, an abrasive wheel mounted on a shaft, said shaft being arranged on said swinging arm and in engagement with said second toothed wheel of smaller diameter, the pyrophorous mass being fastened to said swinging arm.

5. In a toy with a spark producing device formed of pyrophorous mass and scratcher, a handle, a swinging arm rotatably arranged on said handle, a toothed wheel fixed on the axle of said handle, a gear of smaller diameter than said toothed wheel and in engagement therewith, one of said cooperative parts of the spark producing device arranged on a shaft mounted in said swinging arm, said shaft being connected with said gear, a ratchet wheel on the axle of said handle, a flexion spring in engagement with said ratchet wheel and fastened to said swinging arm, the other part of said spark producing device also being fastened to said swinging arm.

6. In a toy with a spark producing device formed of pyrophorous mass and scratcher, a handle, a swinging arm rotatably arranged on said handle, a toothed wheel fixed on the axle of said handle, a second toothed wheel of smaller diameter than said first one and in engagement therewith, one of said cooperative parts of the spark producing device arranged on a shaft mounted in said swinging arm, said shaft being connected with said second toothed wheel of smaller diameter and the other part of said spark producing device being fastened to said swinging arm, said swinging arm being formed of a U-shaped elastic frame.

7. In a toy with a spark producing device formed of pyrophorous mass and scratcher, a handle, a swinging arm rotatably arranged on said handle, a toothed wheel fixed on the axle of said handle, a second

toothed wheel of smaller diameter than said first one and in engagement therewith, one of said cooperative parts of the spark producing device arranged on a shaft mounted in said swinging arm, said shaft being connected with said second toothed wheel of smaller diameter and the other part of said spark producing device being fastened to said swinging arm, said swinging arm being formed of a U-shaped metallic strip.

8. In a toy with a spark producing device formed of pyrophorous mass and scratcher, a handle, a swinging arm rotatably arranged on said handle, a toothed wheel fixed on the axle of said handle, a second toothed wheel of smaller diameter than said first one and in engagement therewith, one of said cooperative parts of the spark produc-

ing device arranged on a shaft mounted in said swinging arm, said shaft being connected with said second toothed wheel of smaller diameter and the other part of said spark producing device being fastened to said swinging arm, said swinging arm being formed of a frame, said toothed wheels and the gears being arranged between the parts of said frame, the cooperative parts of said spark producing device being arranged on the outside of said frame.

In testimony whereof I have hereunto set my hand in presence of two subscribing witnesses.
